UNITED STATES PATENT OFFICE

2,538,470

GATE

Louis H. Peeples, Tulsa, Okla.

Application February 9, 1946, Serial No. 646,655

3 Claims. (Cl. 39—22)

1

This invention relates to gates, and more particularly to an entrance gate for vehicles, interposed in the length of a fence, and adapted to be opened by contact with the bumper of an automobile or other vehicles to open the same when approaching in either direction, and to delay the closing thereof, so that the vehicle may clear the gate before the latter closes.

An object of the invention is to provide novel means for mounting the gate and for releasing a spring catch therefor normally engaged with a keeper when the gate is in a closed position, and to release the catch by bumping engagement of an automobile or other vehicle with mechanism on the gate, and to further provide means for engagement with the gate and on said gate and a post disposed near the free end thereof when open, to delay the closing of the gate.

Another object of the invention is to provide a simple and novel means and construction for the above purpose, which is relatively simple, can be readily applied to a gate and which is not likely to get out of working order.

Other objects and advantages reside in the details of construction and operation as more fully hereinafter described and claimed, reference being had to the accompanying drawings forming part hereof, wherein like numerals refer to like parts throughout, and in which:

Figure 1 is a front elevation of a gate in closed position and showing the impact opening means and the means to delay the closing thereof.

Figure 2 is a plan view of the structure shown in Figure 1 and indicating the gate open in dotted lines.

Figure 3 is an enlarged fragmentary vertical elevation partly in section showing the gate latch and means for delaying the closing of the gate.

Figure 4 is an enlarged elevation partly in section showing the manner of supporting the upper end of the gate.

Figure 5 is a view similar to Figure 4 but showing the manner of supporting the lower end of the gate.

Figure 6 is a sectional elevation taken in the plane of the line 6—6 of Figure 2 with the gate in an open position and showing some of the detail with parts broken away of the means for delaying the closing of the gate.

Figure 7 is an enlarged horizontal sectional view taken on the line 7—7 of Figure 3.

Figure 8 is an enlarged horizontal section taken on the line 8—8 of Figure 3.

Figure 9 is an enlarged horizontal sectional view taken on the line 9—9 of Figure 3.

Figure 10 is an enlarged horizontal sectional view taken on the line 10—10 of Figure 4.

Figure 11 is an enlarged horizontal sectional elevation taken on the line 11—11 of Figure 1.

2

Figure 12 is an end elevation partly in section of the structure shown in Figure 11 and with the chains omitted.

Figure 13 is an enlarged view of the retarding piston, and

Figure 14 is a side view of the piston shown in Figure 13.

Referring to the drawings in detail, the gate is interposed in the line of a fence at a gate opening having a gate supporting post 15 and a keeper supporting post 16 spaced therefrom a suitable distance according to the length of the gate. Both of these posts may be reinforced by braces 17 and 18 as shown extending at an angle from the posts near their upper ends to the ground to effectively support the posts in upright positions. The gate 19 is shown comprising a rectangular frame having a vertical hinge bar 20 near the hinged end and an outer vertical bar 21 near the free end, as distinguished from the inner or hinged end, connected by horizontal upper and lower bars 22 and 23. An intermediate or third horizontal bar 24 is provided between the vertical bars 20 and 21 spaced above the lower bar 23 and spaced a greater distance from the top or upper bar 22 and parallel thereto, while an additional vertical bar 25 is disposed near the free end parallel to the bar 21 and between the upper bar 22 and the bar 24, all of said bars being rigidly connected or welded together as desired and comprising tubular or other suitable metal members. In addition, wires or cables 26 are extended between the bars 20 and 25 horizontally in parallel relation and connected thereto through the medium of loops, U-bolts or the like 27, while a brace 28 extends beneath a web or gusset plate 29 at the corner between the bars 20 and 22, and a similar gusset or web plate 30 at the corner where the bars 24 and 25 join to prevent sagging of the gate. The bar 24 is joined to the inner vertical bar 20 by a flat portion or plate 31 secured to the bar 20 and to the inner end of the bar 24 as by welding or the like, and is apertured to receive a vertical pivot or trunnion 32 which has its lower end provided with a reduced pivot portion 33 engaging an aperture of a similar plate 34 also welded or otherwise secured to the bar 20 below the plate 31 and retained by a cotter pin or the like 35. An arm or bar 36 is rigid with the vertical pivot member 32 and extends inwardly therefrom to a point substantially midway of the length of the gate where it is pivotally connected and supports a horizontal cross-bar 37 through the medium of spaced horizontal jaws or a clevis 38 bolted through apertures vertically in said parts as indicated at 39 to allow pivotal movement of the cross-bar 37 projecting from either side of the gate. Vertically on opposite ends of the cross-bar 37 are metallic channels 40 which are rigid

with the ends of the bar 37 and form receiving and retaining means for rubber or like cushions 41 which are retained in position at the ends 42 of the channels 40 by means of bolts 43 imbedded in the rubber of the cushions or bars formed thereby and extending through apertures in the upper and lower ends of the channels. The channels may be of right angular or other shape, as depicted in the Figures 11 and 12 of the drawings. At intermediate points of their length, the channels are rigidly secured to the ends of the bar 37 extending cross-wise and upon opposite sides of the connection of the arm 36 with the cross-bar 37, the latter is provided with flexible connections or chains 44 converging outwardly and connected to a similar flexible member or chain 45 having its free end adjustably connected to a rod 46 as by means of a turn-buckle 47, one end of which is provided with a hook 48 connected to the chains 45 and the opposite end of which is provided with an eye connected to a loop 49 formed at the inner end of the rod 46 which is in turn connected at its outer end to a normally contracted coil spring 50 having its opposite or outer end connected to the vertical post 21 as at 51 by means of loops, U-bolt and eye or otherwise in connection with a plug 52 on one of the links or loops 51 extending into the adjacent end of the coil spring 50 and locked thereto by a lug 53. A similar plug and lug 52 and 53 respectively are provided between the rod 46 and the inner end of the spring 50 and an adjustable latch release bar 54 is secured to a U-bolt 55 and to the bar 46 and offset upwardly therefrom with means 56 for coupling the sections thereof to render the same adjustable in length and the forwardly extending free end of the loop 55 in its projection in front of the bar 21 vertically at the free end of the gate.

In order to hingedly mount the gate, the inner end of the upper horizontal bar 22 of the frame 19 of the gate is internally threaded to receive a threaded shank 57 having a vertical open-ended sleeve 58 at its inner end receiving a pivot pin 59 therethrough. A collar 60 is clamped around the post 15 near its upper end and is split to provide a clamp having coacting apertured jaws 61 bolted to the post 15 as indicated at 62 as shown in Figures 1, 4 and 10 of the drawings. A horizontal plate 63 is welded or otherwise rigidly secured to the collar 60 and extends outwardly therefrom to a point adjacent the vertical bar 20 at the pivoted end of the gate. The plate 63 is provided with an elongated slot 64 near its inner end, in which the pivot pin 59 is adjustably held on either side, by means of nuts 65 threaded on the pin 59 to clamp opposite sides of the plate 63, while adjustment is effected through the medium of a threaded stem 66 threaded through a threaded bore in the end of the plate 63 at its right portion formed with the slot 64, said stem being in the form of a screw and held in adjusted position by a nut 67 threaded thereon against the end of the plate 63 adjacent the threaded bore. In this way, the upper pivoted end of the gate may be held in adjusted position.

At its lower end, the post 15 is provided with a similar collar 60 split and correspondingly held in position on the post, the parts thereof being correspondingly constructed and indicated by reference characters. A shorter flat plate or arm 68, with respect to the plate 63, is provided upon the lower collar 60 and carries a rigid vertical pivot pin 69 offset inwardly with respect to the

pivot pin 59. The pin 69 is engaged by a sleeve 70 formed at the outer end of a threaded stem 71 loose in the inner end of the lower frame member or bar 23 and adapted to be clamped in adjusted position by a nut 72 engaged on the threaded shank or stem 71 against the inner end of the smooth bored lower bar 23 projecting from the vertical bar 20 and also adapted to be held by a set screw 73 threaded through the bar 23 in engagement with the shank 71 as indicated in Figure 5 of the drawings. In this way, adjustment can be made without removing the pivot pin 69 as is the case with stem 57 which is of necessity threaded in bar 22 because the thrust is outward on account of the weight of the gate. The gate is adapted to swing on two pivots spaced horizontally from each other or off center, so as to tend to swing upwardly to an inclined position whereby it will return to a closed position by gravity under the weight thereof from an open position.

The lower pivot plate 34 may be connected at a point intermediate the two lower horizontal bars 23 and 24 by a wire rod or cable 74 to the vertical end bar 21 of the gate frame as indicated at 75 in such a manner as to intersect the vertical bumper or cushion bars 40 and 41 below the arm 36 and chains 44 and 45. The length of the latter vertical bumper bars, provide means for engagement by the bumpers of automobiles or other vehicles at different heights, thereby insuring the actuation of the catch releasing mechanism. The latch bar 76 has a cross-bar 76' and is pivoted at 77 to a bracket 78 comprising spaced ears of U-shaped formation rigidly welded or secured to the vertical bar 21, with its long arm extending downwardly and a short arm extending upwardly. The lower end of the latch bar 76 is engaged by the release loop 55 of release bar or arm 54 and is normally held outwardly by a spring or other resilient means 79 interposed between the latch bar 76 and the vertical bar 21. The pivotal movement of the bar 76 is limited by an adjustable stop member shown in the form of a threaded screw 80 adjustable through the upper end of the latch bar 76 and adapted to be held by a nut 81 threaded thereon, in engagement with the front of the bar 21.

The latch bar 76 is adapted to engage a keeper consisting of a collar 82 of the same construction as the collars 60 and similarly clamped thereon at the post 15 with which the free end of the gate cooperates. An inwardly extending plate 83 is rigidly secured to the collar 82 by welding or otherwise and has pivoted thereon keepers 84 as indicated at 85 on opposite sides and having extensions 86 forming handles by which they may be hand operated. The spaced heads of the latches 84 cooperate to receive the latch bar 76 therebetween and have bevelled outer edges 87, to permit automatic engagement of the latch bar 76 therewith in either direction when closing from an open position at either side of the post 15. The latches 84 are provided with apertured lugs 88 connected by a spring 89 so as to permit movement of the latches in either direction in permitting engagement and disengagement of the latch bar therewith. This is facilitated by spacing the inner sides or edges of the latches 84 as indicated at 90, it being understood that the lower end of the latch bar 76 at its point of engagement by the arm 54 is received within the loop 55 formed at the free end of the arm 54 as shown in Figure 7 of the drawings, so that when the bumper of a car strikes the vertical bumper

members 41, the cross-bar 37 will be pivoted to retract the chain 45 and the latch release arm or bar 54, thus moving the latch bar 76 on its pivot 77 to disengage the latch bar from the keepers 84 while expanding the spring 50 and compress spring 79, and upon release thereof, permitting the spring 50 to contract and provide a force to swing the gate open when the latch is disengaged by a push by an automobile which should be in low gear. Latches 84 are limited in their movements outwardly away from each other on pivots 95 under the action of spring 89 by inward projections 90 engaging beveled ends of a vertical projection 91 on plate 83, but are free to move inwardly when engaged by latch bar 76 on the gate against beveled edges 87 from either side. More push or thrust is not necessary after the latch releases. When the gate closes, the latch bar 76 under the action of its spring 79 will again engage the keepers. This action is automatic upon the closing of the gate from either side, upon being swung to an open position at either side by reason of the opposite projection of the bumper bars from the opposite sides of the gates. This action is also facilitated by reason of the pivotal mounting of the horizontal arm or bar 36 on which the bumper bars are provided.

In order to momentarily hold the gate in an open position at either side and delay the closing thereof, to permit the clearance of the automobile or other vehicle after having passed through the gate opening and opening the gate as described, a third post 91 is disposed upon opposite sides of the gate post 15 and offset outwardly therefrom at either side, one of said posts being shown in Figure 2 of the drawings at a proper distance from the gate post 15 and related thereto rearwardly toward the fence line as shown in Figure 1 of the drawings. Each of these posts 91 is provided with a collar 92 similar to the collars 60 and 82 and clamped thereto in the same manner. At the inner side of each collar 92, an inclined track or rod 93 is provided rigidly fixed thereto as indicated at 94 with its lower end turned horizontally or upwardly as indicated at 95. Between the bars 21 and 25 spaced in parallel relation vertically at the free end of the gate frame, a retarding means is provided consisting of a hydraulic cylinder 96 extending vertically and pivoted to the adjacent portion of the horizontal bar 24 as indicated at 97 to swing laterally on said pivot or rigid therewith if desired, as shown in Figure 6 of the drawings. The cylinder 96 is provided with a bypass 98 connected to opposite ends of the cylinder internally and having a controlled needle valve 99 at one end to regulate the flow of the oil or other fluid contained within the cylinder, from one end of the cylinder to the other. A piston 100 operates in the cylinder 96 and its rod 101 passes through a packing gland 102 and nut 103 on the piston rod at the head or top end of the cylinder and carries a U-shaped yoke or fork 104 adjustably on its upper end in which a pair of upper and lower spaced rollers 105 are journaled on horizontal shafts having bearings in the tines or vertical legs of the yoke or fork 104.

Also piston 100 is provided with holes 100' which are drilled through it between the center and outside circumference and which are covered at the lower end of the piston by a disc or valve 101' which unseats downwardly and lets the fluid pass through holes 100' allowing the piston to move upward quickly when upper roller 105

strikes arm 95. The disc 101' seats upwardly and leaves only the bypass 98 for the fluid to pass through as the piston comes down thus allowing the piston to move downward very slowly. The piston rod 101 does not pass through the piston but is screwed into it only a short way and is secured by a lock or jam nut 102'.

The disc or valve is held in place by a small screw 103' through the middle but which is of just the right length to allow the disc to drop away from the piston slightly as the piston moves upward thus allowing the fluid to pass through the piston instead of or in addition to the bypass 98. Thus, no rings or packing are needed on the piston because the fluid furnishes all the seal that is necessary between the piston and the cylinder wall. The ends of the shafts of rollers 105 carry rollers 106 which operate in vertical channels or guides 107 fixed to the bars 21 and 25 so as to guide the rollers 105 and 106 vertically therein during the reciprocation of the piston 100 and the piston rod 101 as a retarding and cushioning means determined by the volume of fluid passing through the holes or passages 100' as disc or valve 101' uncovers holes 100' and through the duct or bypass 98 during the downward movements or reciprocation of the piston 100 within the cylinder 96 when the holes 100' are closed by disc 101'. The inclined track or arm 93 is adapted to engage angularly between the rollers 105 when the gate is swung to an open position toward the post 91 at either side of the gate opening and raise the piston 100 within the cylinder 96, so that its downward movement along the inclined track as the rollers 105 move thereon, will be retarded by the fluid within the cylinder to momentarily delay and retard the closing of the gate when in an open position, so that the vehicle may pass there-through without obstruction and clear the gate before the latter closes. This action is automatic, since the rollers 105 are so positioned as to be engaged by the inclined track or rod 93, assisted by the horizontal or upturned portion 95 and the spacing of the rollers 105 a greater distance than the thickness of the track 93 as particularly shown in Figures 3 and 6 of the drawings, while the rollers are guided by the trackways formed by the vertical channels 107 on the posts 21 and 25, in their reciprocating or up and down movements when actuated in the manner just described.

Thus, with the gate closed and the latch bar 76 engaged with keepers 84, between the spaced inner edges thereof, when the bumper of the automobile strikes the cushion bars 41, the latter will be swung to one side or the other and thus swing the cross-bar 37 on its pivot. By reason of the connection of the cross-arm or lever formed by the bar 37 through the chains 44 and 45, providing a flexible connection with the latch release arm 54 and loop or U-bolt 55 which engages the lower end of the latch bar 76, the latter is moved inwardly on its pivot 77 to disengage the latch bar 76 from the keepers 84 and permit the gate to open under further impact. Inasmuch as the hinge pins or pivots of the gate are spaced horizontally or off center and the lower pivot is fixed while the upper pin is adjustable, the gate will tend to swing to an inclined position so that it will automatically return to a closed position by gravity. As the gate swings to an open position toward one of the posts 91, the inclined track 93 will engage between the rollers 105 and elevate the piston. In the closing of the gate, the

movement of the gate to a closed position will be momentarily restrained or retarded by the piston or hydraulic retarding means, so that the vehicles can clear the gate opening and the gate before the latter closes. Upon the gate swinging to a closed position, the latch bar 76 will automatically move between the keepers 34 and be held in a closed position.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. In a gate, a gate post, a gate hinged to said post, a keeper member suitably supported adjacent the free end of the gate and comprising a collar adapted to be clamped to a gate post and having pivoted keepers, means to hold said keepers separated, means to limit the closing of the keepers in spaced relation, an arm pivoted to the hinged end of the gate and extending horizontally, a cross bar pivoted to said arm at its free end intermediately of the length of the gate and having impact members vertically at the ends thereof at opposite sides of the gate, a release bar connected to the cross bar at opposite sides of its pivot and having a resilient connection with the free end of the gate to normally hold the cross bar at right angles to the length of the gate, a pivoted latch bar extending vertically of the free end of the gate, means to adjust and limit the movement of the latch bar, said latch bar being engageable between the keepers and a loop at the free end of the release bar to engage around the lower end of the latch bar to disengage the latter from the keepers upon impact with an impact member and swinging of the cross bar.

2. In a gate, a gate suitably hinged, a post supported at a distance from the gate equal to the length of the gate, a rigid inclined track carried by said post, a cylinder mounted vertically on the gate near its free end, a piston operating in said cylinder, a bypass connecting opposite ends of the cylinder, said piston having a rod operating through the upper end of the cylinder, spaced rollers mounted on the upper end of the piston rod adapted to be engaged by said track to raise the piston when the gate is opened and tracks mounted on the gate guiding said rollers up and down in the opening and closing move-

ments of the gate, said piston having valve means therethrough to permit quick opening of the gate and to retard the closing of the gate to cause slow closing thereof.

3. In a gate, a post, a gate comprising a frame hinged to the post, a second post, keepers carried by the second post, a latch bar pivoted on the free end of the gate to engage said keepers, said gate having horizontal members between the hinged and free ends thereof forming part of the gate frame, a horizontal bar pivoted to the hinged end of the gate, a cross bar pivoted intermediately to said horizontal bar at its inner end intermediate the length of the gate, vertical cushion members mounted on the ends of said cross bar and projecting from either side of the gate, adapted to cause swinging of the cross bar upon impact of an automobile bumper or vehicle therewith, a release arm projecting from the free end of a gate and looped around the lower end of the latch bar, means normally projecting the free end of the release arm from the free end of the gate, and adjustable flexible connections between said release arm and the cross bar upon opposite sides of the pivot thereof to cause retraction of the release arm upon pivotal movement of the cross arm to disengage the latch bar from the keepers, whereby further impact with the cushion members will cause opening of the gate.
